CLAIM

The ornamental design for a bag interior illumination device, as shown and described.

DESCRIPTION

FIG. 1 is a front view of a bag interior illumination device showing my new design;

FIG. 2 is a rear view of the bag interior illumination device; FIG. 3 is a left side view of the bag interior illumination device;

FIG. 4 is a right side view of the bag interior illumination device;

FIG. 5 is a top view of the bag interior illumination device; and,

FIG. 6 is a bottom view of the bag interior illumination device.

The broken lines portions of the article which form no part of the claimed design.
